UNITED STATES PATENT OFFICE.

PEYTON B. GRAVELY AND ROBERT W. LAWSON, OF DANVILLE, VIRGINIA.

DESIGN FOR PLUG-TOBACCO.

SPECIFICATION forming part of Design No. 11,892, dated July 27, 1880.

Application filed October 4, 1879. Term of patent 14 years.

To all whom it may concern:

Be it known that we, PEYTON B. GRAVELY and ROBERT W. LAWSON, of Danville, in the county of Pittsylvania and State of Virginia, 5 have originated and invented a new and useful Design for Plug-Tobacco; and we do hereby declare that the following is a full, clear, and exact description thereof, reference being had to the accompanying drawing, forming a part 10 of this specification.

Referring to the annexed drawing, which clearly illustrates the nature of our design, A designates a tobacco rope, which, commencing at *a*, is continued so as to form a loop, *b*; thence 15 upward and around the end *a*, and then brought back upon itself and through the loop *b*, so as to form a loop, *c*. These two loops have the general appearance of a fancifully-designed figure 8. After forming the second loop, *c*, the 20 rope is still farther carried on and given a half-coil, so as to form a loop, *d*, and thence it is carried along and passed through the first loop, *b*, and then back upon itself, so as to form the

final loop, *e*; after which its end is carried into the loop *d*, where it disappears. 25

In this peculiar interlacing of the rope a slab, almost square, is formed. The general appearance of the slab thus formed is that of two pairs of double loops interlocking with each other by an easy and graceful series of 30 curves.

What I claim is—

The design for a tobacco slab, composed of the four loops *b c d e* at the four corners of the slab, the loops *b e* interlocking with each other, 35 and the loops *c d* interlocking together, and the rope *A* being carried through all of the loops which it forms, as shown and set forth.

In testimony that we claim the foregoing as our own we affix our signatures in presence of 40 two witnesses.

PEYTON B. GRAVELY.
ROBERT W. LAWSON.
